UNITED STATES PATENT OFFICE.

WILLIAM U. GRIFFITHS, OF PHILADELPHIA, PENNSYLVANIA.

MECHANISM FOR WATER-CLOSET APPARATUS.

1,306,058.

Specification of Letters Patent. Patented June 10, 1919.

Application filed January 12, 1915. Serial No. 1,723.

To all whom it may concern:

Be it known that I, WILLIAM U. GRIFFITHS, a citizen of the United States, and a resident of Philadelphia, in the county of 5 Philadelphia and State of Pennsylvania, have invented certain new and useful Improvements in Mechanism for Water-Closet Apparatus, of which the following is a specification.

10 Broadly my invention has for its object to simplify the construction of mechanism for controlling a supply of water employed for flushing the bowl of a water closet apparatus. A further object of my invention 15 is to provide means whereby the possibility of leakage of water from the conveying conduit prior to its reaching the closet bowl is avoided.

My invention comprehends the construction and arrangement of parts as herein-after described in the specification and set forth in the claims.

20 In the accompanying drawings I have illustrated a preferred form of embodiment 25 of my invention but it is to be understood that changes in the details of construction may be made within the scope of the claims without departing therefrom.

In the drawings:

30 Figure 1 is a longitudinal sectional view of a portion of the conduit for supplying the water for flushing a water closet bowl, showing the parts embodying my invention partly in side elevation and partly in section;

35 Fig. 2 is a top plan view of the construction shown in Fig. 1, a portion of pipe shown at the top of said Fig. 1 being omitted; and

40 Fig. 3 is a transverse sectional view taken on the line 3—3 of Fig. 1.

In the drawings, 1 designates a portion of a supply conduit for supplying water from the street main for flushing a water closet 45 apparatus. In the construction as illustrated the portion 1 of the conduit is in alinement with an extension pipe 2 which extends to a flush tank (not shown). When the valve mechanism, indicated as a whole 50 at 3 in Fig. 1, is opened to permit the water to flow into and through the portion 1 of the conduit it flows forwardly through the pipe 2 into a flush tank (not shown). Intermediate the pipe 1 and the extension pipe 55 2 a fitting 10 is provided the main channel 11 of which is in alinement with the pipes

1 and 2. The said fitting is provided with a hollow lateral projecting portion 12 in the chamber of which a lever 13 is pivoted. The said lever is supported upon the side 60 walls of the said projecting portion 12 by means of trunnions 14 and 15 which project from an intermediate part of the lever into holes formed in the bosses 16 and 17 upon the opposite sides of the said hollow projecting portion. These bosses project inwardly as shown in Fig. 3 of the drawings. The side wall upon which the boss 17 is formed and from which it projects is removable as is apparent from Figs. 2 and 3 70 of the drawings in order to permit the placing of the lever 13 in the chamber of said projection.

One end of the lever 13 is provided with an open slot 18 whereby said end is bifurcated to permit it to straddle the rod 20 immediately underneath the head 19 which is secured to the upper end of the said rod. The valve mechanism for controlling the flow of water from the street main into 80 the portion 1 of the pipe is secured to the lower end of the rod 20. 21 designates a rod of relatively small diameter which is secured to the said head 19 and is extended in alinement with the rod 20 and projects through a 85 central opening formed in a plate 22 supported upon a shoulder 23 at the upper end of the channel 11 of the fitting 10. The plate 22 is provided with openings 24 for the passage of water and said plate is held 90 in position by the lower end of the pipe 2. Interposed between said plate and the head 19 is a coiled spring 25 which holds the rod 20 normally in its lowermost position with the valve mechanism at 3 closed. The 95 other or opposite end of the lever 13 is provided with an opening 26 through which the lower end of a valve rod 27 projects.

Adjacent to its lower end the said valve rod is provided with a laterally extending 100 flange 27^a which rests upon the upper side of the lever 13 adjacent to the opening 26 therethrough. The rod 27 extends upwardly from the chamber within the hollow projection 12 through an opening 28 in the 105 upper side of the said projection into a chamber 29 formed above the said upper side. The upper end of the rod 27 is provided with a flange 30. The open upper end of the chamber 29 is closed by means 110 of a cover 31 and a diaphragm 32. The cover is provided with a flange 33 the lower

inside portion of which is cut away to form a shoulder as indicated at 34. The inside portion of said flange below the shoulder is screw-threaded and is adapted to engage 5 screw-threads 35 upon a flange 36 which extends above and surrounds the open upper end of the chamber 29. The outer edges of the diaphragm 32 rest upon the top of edge of the flange 36 and are clamped in such 10 position by means of the shoulder 34 when the cover 31 is screwed down upon the flange 36 as is indicated in Fig. 1 of the drawings. The diaphragm 32 forms a seal for the open end of the chamber 29 and prevents 15 the leakage of water therefrom. The center of the diaphragm 32 is provided with an opening and the portion of the said diaphragm immediately surrounding the said opening rests against the flange 30 upon the 20 valve rod 27 and is clamped and held against said flange by means of a flange 37 upon a member 38 which is adapted to be connected to the upper end of the rod 27 in known manner. The part 38 constitutes in 25 effect an extension or continuation of the rod 27 and it extends through a central opening 39 in the cover or closure 31.

The rod 27 is provided intermediate its 30 ends with a valve 40 which is adapted to close the opening 28 through which the rod 27 extends into the chamber of the lateral projection 12.

42 designates a lever connected intermediate its ends at 43 to the upper end of the extension part 38. The inner end of said lever 42 is provided with a yoke 44 the opposite sides of which are positioned upon the opposite sides of the upper end of the part 10 of the fitting and are pivotally secured thereto 40 by means of projecting bolts 45. The opposite end of the said lever extends forwardly beyond its point of connection to the part 38 and is adapted to be operated by means of the pivotal movements of the water closet 45 seat as it is moved toward and from the water closet bowl. The end 46 of the said lever is so positioned with respect to the water closet seat that when the latter is depressed the end 46 of said lever is also depressed causing movement of said lever about its pivots 45 to depress the rod 27, carrying the valve 40 into engagement with the upper side of the top wall of the hollow lateral projection 12 so as to close the opening 28 therein. Such movement occasions downward movement of the end of the lever 13 with which the flange 27^a on the lower end of the rod 27 contacts. Downward movement of said end causes an upward movement of the other or opposite end of the said lever which is in engagement with the rod 20 underneath the head 19 to raise the said rod and thereby move the valve at 3 into open position so that the water can flow upwardly through the pipes 1 and 2 into the

flush tank. Upon release of pressure from the seat the action of the spring 25 causes movement of the parts 20, 13, 27, 27^a, 38, 40 and 42 in the opposite direction from that just described. As a result the valve 70 at 3 is moved into closed position while the valve 40 is opened to permit water to flow in reverse direction through the pipe 2, through the hollow projection 12, and thence through the opening into the chamber 29 and thence 75 through the pipe 50 and extensions of the same into the water closet bowl (not shown) to flush the same.

It will be understood that when the water 80 is flowing from the flush tank through the chamber 29 it exerts considerable pressure in the latter with the result that there is a tendency to leakage. Leakage, however, is prevented if a diaphragm such as 32 is employed having its edges clamped between the 85 shoulder 34 and the top of the flange 36 and its central portion clamped by the clamping flanges 30 and 37 as indicated in Fig. 1 of the drawings.

By reason of the construction as described 90 in which the lever 13 is provided with a bifurcated end which straddles the rod 20, the latter together with the valve secured to the lower end thereof may be removed from the pipe 1 by removing the plate 22 and thereafter drawing said rod and valve upwardly through said pipe and through the bifurcated end of said lever. Also the rod 27, the part 38 and the valve 40 may be removed merely by disconnecting the part 38 95 100 from the lever 42 and removing the cap or cover 31. One advantage of the construction as described is that it allows the removal of these parts as described without removing the lever 13.

Claims:

1. In mechanism for water closet apparatus, the combination of a water supply conduit, a rod in said conduit having a valve secured thereto for closing said conduit and having means at its upper end forming a shoulder, a hollow projection extending laterally from said conduit, a lever situated in said projection and pivoted intermediate its ends, one of its ends having an opening therethrough through which the said rod extends said end being situated immediately underneath said shoulder, and the opposite end of said lever being provided with an opening, a valve rod extending into said hollow projection and having its lower end projecting through said opening and also having means thereon for engaging said lever to depress the same and an operating lever outside of said chamber pivotally supported at one end and having engagement intermediate its ends with the said valve rod for operating the same.

2. In mechanism for water closet apparatus, the combination of a water supply 130

conduit, a rod in said conduit having a valve
secured thereto for closing said conduit and
having means at its upper end for forming a
shoulder, a hollow projection extending lat-
5 erally from said conduit, a lever situated in
said projection and pivoted intermediate its
ends one of its ends being bifurcated, said
bifurcated end straddling said rod immedi-
ately underneath said shoulder and the op-
10 posite end of said lever being provided with
an opening, an open-ended chamber secured
to said projection said chamber communicat-
ing with the interior of the said hollow pro-
jection by means of an opening through the
15 wall of the latter, removable means for clos-
ing said chamber, a valve rod extending
through said chamber and through the open-
ing between the said chamber and the said

hollow projection into the latter said valve
rod extending into the opening in the said 20
lever and having means in contact with the
said lever whereby when the said valve rod
is operated the said lever is also operated,
and an operating lever outside of said cham- 25
ber pivotally supported at one end and hav-
ing engagement intermediate its ends with
said valve rod for operating the same and
thereby operating the lever in the hollow of
said projection, substantially as described.

In testimony that I claim the foregoing as 30
my invention I have hereunto signed my
name this 11th day of January, A. D. 1915.

WILLIAM U. GRIFFITHS.

In the presence of

CYRUS N. ANDERSON,
FLORENCE DEACON.
